CLAIM

The ornamental design for a financial services card, as shown and described.

DESCRIPTION

FIG. 1 is a front view of an embodiment of our financial services card.

FIG. 2 is a back view of the embodiment of FIG. 1.

FIG. 3 is a top view of the embodiment of FIG. 1.

FIG. 4 is a bottom view of the embodiment of FIG. 1.
